Patented Aug. 16, 1921.

UNITED STATES PATENT OFFICE.

NICHOLAS MOLLET, OF MASSILLON, OHIO.

SIGN.

1,387,933.

Specification of Letters Patent. Patented Aug. 16, 1921.

Application filed April 11, 1921. Serial No. 460,326.

To all whom it may concern:

Be it known that I, NICHOLAS MOLLET, a citizen of the United States, residing at Massillon, in the county of Stark and State 5 of Ohio, have invented certain new and useful Improvements in Signs, of which the following is a specification.

The present invention relates to an advertising sign which is especially designed for 10 outdoor use, and which embodies novel features of construction whereby sign cards can be displayed in an attractive manner so that the attention of passers-by is almost certain to be directed thereto.

15 In carrying out the invention a plurality of sign card receiving frames are joined together to provide a balanced frame structure which is mounted in a novel manner upon a post or like support so that it is rotatable thereon and will be moved by the 20 pressure of the wind. This movement or rotation of the sign card carrying structure will serve to attract attention to the sign cards and a most effective advertising display will thereby be provided.

For a full understanding of the invention, reference is to be had to the following description and accompanying drawings, in which:

30 Figure 1 is a front elevation of a double faced road sign which is constructed and mounted in accordance with the invention.

Fig. 2 is a side elevation thereof, looking at the same from a position at right angles 35 to that of Fig. 1.

Fig. 3 is a horizontal sectional view on the line 3—3 of Fig. 1, looking in the direction of the arrows.

Fig. 4 is a detail view of a fragmentary 40 portion of the supporting post, illustrating a possible modification in which the post is provided with bearing grooves for the supporting of the rotatable sign carrying structure.

45 Fig. 5 is a sectional view on the line 5—5 of Fig. 4.

Figs. 6, 7 and 8 are detail views showing a modified construction of bearing plate for supporting and retaining the revolving 50 structure upon the post.

Corresponding and like parts are referred to in the following description and indicated on all of the views of the drawing by like reference characters.

55 In the embodiment of the invention which is shown by the drawing for illustrative

purposes, the numeral 1 designates a supporting post which may be erected, preferably in an upright position, in any suitable place. The sign or advertising cards 2 are 60 fitted in frames 3, said frames forming a part of a balanced and skeleton structure which is rotatably mounted upon the post so that it will be acted upon and intermittently rotated from time to time by wind 65 pressure. In the present instance there are two of the frames 3 which are symmetrically supported upon opposite sides of the post. These frames are similar in size, shape and construction, and the display 70 cards 2 are preferably fitted within the frames so that they can be removed and replaced as often as desired. An advertiser may thus change his display by substituting new sign cards for the old sign cards, and 75 the sign structures themselves may be owned by concerns selling space thereon to different advertisers for different periods of time. The signs 3 have the intermediate cross pieces 3^a which brace and stiffen the 80 same, and are rabbeted in the usual manner to receive the edges of the sign cards 2, as indicated at 4. Retaining strips 5 are fitted in the rabbeted portions of the frames and hold the sign cards removably in position. 85

The two frames 3 are connected by cross pieces 6 of which the intermediate portions are bowed at 6^a, while the end portions are bent laterally in opposite directions to provide feet 6^b which are secured to the frames 90 3. Bowed keepers 7 are secured to the intermediate portions of the cross pieces and coöperate therewith to provide rings or looped portions loosely receiving the post 1.

The structure thus provided has a balanced 95 and symmetrical formation and is loosely mounted upon the post so that it can be moved or rotated intermittently by the wind pressure. Owing to the symmetrical arrangement of the structure, however, substantially the same amount of surface is exposed to the action of the wind on each side of the axis of the post, so that there will be no violent action or undue strain, such as would tend to throw the supporting post 100 out of position, even when a strong wind is blowing. Regardless of the direction from which the wind is coming, or the position of the revolving structure upon the post, substantially the same surface is always 105 presented to the wind pressure on opposite sides of the axis of the post.

110

The revolving structure may be supported upon the post in different ways. According to the construction shown by Figs. 1, 2 and 3, the rings or looped portions formed in connection with the cross pieces 6 fit loosely upon the post and are engaged at the top and bottom of the sign by bars or plates 8 which are removably secured to opposite sides of the post and are of such a length that the 10 ends thereof project laterally and engage the ring portions of the cross pieces. The lower set of plates 8 thus provide a bearing for supporting the rotating structure, while the upper set of plates provide a retaining means 15 to hold the structure in position. These plates or bars provide a very inexpensive and at the same time secure and practical means for mounting the revolving structure on the post.

20 A slight modification is shown by Figs. 4 and 5, in which the post is shown as provided with bearing grooves 10. These bearing grooves are intended to be of such a size as to receive the intermediate ring portions of the cross pieces or bars 6 and, if desired, the edge portions of the grooves may be suitably reinforced by metal plates to prevent undue wear thereon.

25 A further modification is shown by Figs. 6, 7 and 8, in which the cross pieces 6 at the top and bottom of the frame are engaged by plates 11. Two of these plates are provided at both the top and bottom of the structure and each plate is shown as being 30 substantially semi-circular in shape. The middle portions of the plates are slit to provide the triangular ears 11^a which are bent upwardly to provide means for securing the plates in position. The two plates thus provide in effect a substantially circular plate 35 with a central opening to receive the post, the edge portions of the plate projecting laterally from the post to engage the bearing rings of the revolving structure.

40 It will be obvious that many modifications and changes can be made in the details of construction without departing from the spirit of the invention, and the particular embodiment of the invention which has been 45 shown by the drawings is to be considered in an illustrative sense and not in a restrictive sense.

Having thus described my invention what I claim as new and desire to secure by Letters 50 Patent is:

55 1. In a display sign of the character described, the combination with an upright supporting post, of plates applied to the post and projecting laterally therefrom, a 60 pair of similar sign card receiving frames arranged upon opposite sides of the post in

a substantially spaced and parallel relation, upper and lower cross pieces rigidly connecting the sign card receiving frames and provided at intermediate points in their lengths 65 with bearing rings which loosely receive the post to permit of the frames rotating about the post, one of the bearing rings resting upon the projecting portion of the plates.

2. In a display sign device of the character 70 described, the combination with an upright supporting post, of a pair of similar sign card receiving frames arranged upon opposite sides of the post and having a substantially spaced and parallel relation to each 75 other, cross pieces rigidly connecting the said frames and having bowed portions at intermediate points, and keepers applied to the bowed portions of the cross pieces for coöperation therewith to provide bearing 80 rings which loosely receive the supporting post to hold the frames rotatably in position thereon, said post being provided with means coöoperating with the bearing rings to support the frames.

85 3. In a display sign device of the character described, the combination with an upright supporting post, of a pair of similar card receiving frames arranged upon opposite sides of the post and having a substantially 90 spaced and parallel relation, cross pieces extending transversely between the frames, intermediate portions of the cross pieces being bowed while the extremities thereof are bent laterally to provide feet which are 95 rigidly attached to the frames, and keepers applied to the bowed portions of the cross pieces for coöperation therewith to provide bearing rings which loosely receive the post to rotatably support the frames thereon, said 100 post being provided with means for engagement with the bearing rings to support the frames.

4. In a display sign device of the character 105 described, the combination with a supporting post, of corresponding plates applied to opposite sides thereof and projecting laterally on both sides thereof, a plurality of card receiving frames in which display cards are adapted to be removably fitted, said frames 110 being similar in size and shape and being arranged about the post in balanced relation, upper and lower cross pieces rigidly connecting the frames and provided at intermediate points in their lengths with bearing 115 rings which loosely receive the post and rest loosely upon the projecting ends of the before mentioned plates to rotatably support the frames upon the post.

120 In testimony whereof I affix my signature.

NICHOLAS MOLLET.
